CLAIM

The ornamental design for a screen with animated graphic user interface, as shown and described.

DESCRIPTION

FIG. 1 is a front view of a first image in a sequence for a screen with animated graphical user interface (GUI) showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 the tenth image thereof;

FIG. 11 the eleventh image thereof;

FIG. 12 the twelfth image thereof;

FIG. 13 the thirteenth image thereof;

FIG. 14 the fourteenth image thereof;

FIG. 15 the fifteenth image thereof;

FIG. 16 is the sixteenth image thereof;

FIG. 17 is the seventeenth image thereof;

FIG. 18 the eighteenth image thereof;

FIG. 19 the nineteenth image thereof;

FIG. 20 the twentieth image thereof;

FIG. 21 is the twenty-first image thereof;

FIG. 22 is the twenty-second image thereof; and

FIG. 23 is the twenty-third image thereof;

FIG. 24 is the twenty-fourth image thereof;

FIG. 25 is the twenty-fifth image thereof;

FIG. 27 the twenty-seventh image thereof;

FIG. 28 the twenty-eighth image thereof; and,

FIG. 29 is the twenty-ninth image thereof.

(Continued)

The subject matter of this design patent includes a process or time period in which an image on a display changes into another image. This process or time period forms no part of the claimed design.

The dotted-line portions of FIGS. 6-8, and 25 do not form part of the design. The dash-dash broken lines shown in the Figures, illustrate the boundary of the claimed design, with all dash-dash broken lines in FIGS. 6, 7, 9, 10, 11, 13, and 29 that are within the claimed boundary—forming a part of the claimed design, while the dash-dot-dash broken lines in the Figures, illustrate the borders of the display screen. None of the outermost dash-dash broken lines or the dash-dot-dash broken lines forms any part of the claimed design.
